UNITED STATES PATENT OFFICE.

SIMON IRVING COPEN, OF CHELSEA, MASSACHUSETTS.

PASTE TUBE.

Application filed May 22, 1926. Serial No. 110,969.

The object of my invention relates to improvements in collapsible tubes for containing dental tooth paste, and especially to an improvement in the opening in the spout of 5 the tube.

The openings at the spout of the tube at present are formed either round or rectangular, with the result that the paste leaving the opening assumes either a round or rectangular form. I find that these forms have 10 the following objections. The paste has a tendency to fall off the brush before the user has an opportunity to apply it to the teeth. Furthermore, the place where the greatest 15 part of the paste is required, is on the outside and inside of the teeth and around the necks of the teeth. But with the forms of the paste now used and above described, there is no opportunity for the paste to be applied 20 at the surfaces required.

The object of my invention is to form an opening or orifice, that when the paste, as it leaves the orifice, and is put on the brush, will remain on the brush and will be prevented 25 from falling off. And the paste will be so formed that the greater part of the paste will be at the places where the paste is wanted most, i. e. at the necks of the teeth and the surfaces of the teeth.

The invention will be hereinafter considered in detail and specifically claimed. Reference will now be had to the drawing forming a part of this application, wherein there is illustrated a preferred embodiment of my 30 invention, but it is understood that the struc-

tural elements thereof can be varied or changed as for shape, size and form without departing from the spirit of the invention.

In my drawings—

Fig. 1 is a perspective view of the upper 40 part of a tube with the cover removed showing the orifice or opening.

Fig. 2 is a plan view of Fig. 1 showing the orifice somewhat enlarged.

Fig. 3 shows the same orifice as Fig. 2 with 45 ends of the orifice somewhat rounded.

In the drawings, 1 shows in general a collapsible sheet metal tube of tooth paste, having a spout 2 and an opening or orifice 3 of the form shown. The orifice will be about 50 the same width as the width of the bristles in an ordinary tooth brush, with the result that the paste as it leaves the orifice will fit to the top of the bristles and will be prevented from falling off. 55

The greater part of the paste is concentrated at its ends, as shown, with the result that when the bristles are applied to the teeth, the paste at the ends will be in position where it is needed, i. e. near the necks of 60 the teeth, or the gum line and the surfaces of the teeth.

Having described my invention, what I claim is:—

1. A collapsible paste tube having a double concaved shaped discharge orifice. 65
2. A collapsible tube having a discharge orifice of which at least one side is concave.

S. IRVING COPEN.
